UNITED STATES PATENT OFFICE.

WILLIAM MENDHAM, OF PHILADELPHIA, PENNSYLVANIA.

IMPROVEMENT IN PAPER-FOLDING MACHINES.

Specification forming part of Letters Patent No. 99,336, dated February 1, 1870; antedated January 15, 1870.

To all whom it may concern:

Be it known that I, WILLIAM MENDHAM, of the city of Philadelphia, in the State of Pennsylvania, have invented certain new and useful Improvements in Paper-Folding Machines; and I do hereby declare the following to be a full and correct description of the same, reference being had to the accompanying drawings, in which—

Figure 1 is a longitudinal section of the packing-trough having a reciprocating plunger. Fig. 2 is a similar section of the same, showing a vibrating plunger. Fig. 3 is a plan of the packing-trough shown in Fig. 1. Fig. 4 is a plan of the packing-trough shown in Fig. 2. Fig. 5 is a perspective view of a folding-machine with my improvements applied. Fig. 6 is a transverse vertical section of the first set of rollers, showing the shield and points in the position they occupy when the first knife is up.

The same part is marked by the same letter of reference wherever it occurs.

My improvements consist, first, in devices for preventing the sheet of paper, after it is fed over the upper of the first pair of rollers, from being carried around with that roller and entering endwise between the first pair, instead of passing down in front of them, to receive the blow of the knife and be carried in by its folded edge.

My second improvement consists in devices for supporting the folded sheet as it passes from the last pair of rollers to the packing-trough, the sheet being supported on its folded edge either in a vertical position or at any desired angle. The object of this improvement is to prevent thin, soft, or wet paper from doubling down when not sufficiently rigid to bear the fall from the rollers to the trough, and also to hold the sheet in proper position until the packing-plunger acts upon it.

To carry out my first improvement I employ a shield, which, at the moment the forward edge of the sheet of paper reaches the level of the line of contact of the first pair of rollers, is brought in front of said line, and, in conjunction with the curved ends of the first pair of supporting-wires, bears the end of the sheet off from the rollers and allows the sheet to descend by gravity till it receives the blow of the first folding-knife, and is carried in by its folded edge between the rollers.

For my second improvement I make use of guides or recesses, either vertical or inclined, to receive and support the edges of the sheet as it falls or slides down from the last pair of rollers into the packing-trough, to be there subjected to the action of the reciprocating or vibrating packing-plunger.

The folding-machine represented in the accompanying drawings as having my improvements applied is of the form and construction known as the "Chambers" patent, and its mode of operation is too familiar to need minute description. The sheets to be folded are supported on a table (not shown) attached to frame A, and which covers the upper part of the machine. Motion being given to the operative parts by power applied to the main shaft B, the sheets are fed by the operator between the small roller G and the upper roller, H, of the first pair, H I. It passes over this roller and falls until its middle comes opposite the line of contact of rollers H and I. It then receives the blow of the first knife and passes by its folded edge between the first pair of rollers and back on rods J J' under the second knife, K. This forces it in between the second pair of rollers, L L', whence, having received a second fold, it passes under knife M, and is driven between the last pair of rollers, N N', and, receiving its last fold, falls into the packing-trough Q, and is driven by plunger V against the spring-slide U, which moves back to make room for the sheets as they successively fall into the box.

In the face of roller H grooves *h h* are cut, which receive the curved or hooked ends *i* of the supporting-wires J J' in the manner clearly shown in Figs. 5 and 6.

C C' are levers operated by a cam on shaft B. They are connected by rods D D' to the ends of the first folding-knife, F, attached to eccentric arms *f*, which move eccentrically on the shaft of the roller H. To these rods D D' is attached the shield E in the position shown in Fig. 5. When the levers C C' rise the knife F rises to a position somewhat higher than that in which it is shown in Fig. 5, and the shield is in the position shown in Fig. 6, the knife being outside and the shield inside of the pendant sheet, for the sheet, in passing over the roller H, is borne off from the roller by the curved points *i* of the rods J J', and its end

passes over the edge of the shield and is barred by it from passing between the rollers. It falls by its weight till its middle comes opposite the line of contact of the rollers, when the levers C C' are driven down and draw down the shield E and drive the knife F between rollers H I, carrying the sheet through by its folded edge. After passing the intermediate knives and rollers, receiving successive folds, the sheet passes between the last pair, N N', and falls or slides into the packing-trough. As it leaves these rollers it is received between vertical guides P P', (see Fig. 1,) which conduct it in front of a reciprocating plunger, R, connected by rod S to rock-shaft T, by which it is operated. This plunger packs a sheet at each stroke against the spring-slide U, which gradually recedes in the trough as the number of packed sheets increases.

If preferred, inclined guides W W' may be used, as shown in Figs. 2 and 5, with a vibrating plunger, V, the operation being substantially the same, the only difference being that

the fall of the sheets is somewhat broken by the inclination of the surface along which they descend to the packing-trough. The vibrating plunger is operated by a rocking shaft, as shown.

Having thus fully described my invention, what I claim, and desire to secure by Letters Patent, is—

1. The shield E, arranged and operating as and for the purpose described.
2. The curved points *i i*, arranged for conjoint operation with the shield E in the manner set forth.
3. The guides P P' or W W', for conducting the folded sheet from the last pair of rollers to the packing-trough, as described.

The above specification of my said invention signed and witnessed at Philadelphia this 9th day of June, A. D. 1869.

WILLIAM MENDHAM.
